JOURNAL BOX

Howard T. Casey, Rochester, N. Y., assignor to
The Symington Company, New York, N. Y., a
corporation of Maryland

Application October 26, 1928, Serial No. 315,288

22 Claims. (Cl. 308—47)

This invention relates to journal boxes and more particularly to articulated or two piece lids normally closing the outer openings therein.

The principal object of my invention, generally considered, is to provide a two piece self-adjusting lid for closing the journal box opening, said lid preferably involving a hood or spring housing and a lid proper between which a torsion spring is positioned, said spring having a pair of coils normally seated on the hood, an intermediate loop normally engaging the hinge lug and depending ends of the spring engaging the means connecting said lid proper and housing.

Another object of my invention is to provide a two piece lid in which the actuating spring is positioned between the hood and lid proper with the coils of the spring seated on the hood and the free ends thereof resting on the connecting means between the hood and lid, which in turn engages the lid adjacent the center thereof, thereby maintaining spring tension between the elements of the lid and preventing rattling even when open.

A further object of my invention is to provide a journal box lid having a hood pivoted thereto adjacent its center for inclosing an associated torsion spring, said spring having coils seated on the hood and extending into depressions in the face of the lid, an intermediate loop portion being adapted to engage the hinge lug on the associated box for holding the lid in open or closed position, the free ends or tails of the spring being supported directly on the means pivoting the hood and lid so that the pressure thereof does not tend to cause relative rotation between said parts.

A still further object of my invention is to provide a two piece journal box lid comprising a preferably pressed closure member and malleable spring housing, said closure member being formed with loops extending outwardly from the front face thereof, a pin extending through said loops and corresponding apertures in the housing and a spring received between said housing and lid proper with the lower ends received in corresponding apertures in the pin, thereby serving to lock said pin in place and the loops being formed with lateral projections overlying the ends of said spring for limiting relative movement between said lid proper and housing.

Other objects and advantages of the invention relating to the particular arrangement and construction of the various parts will become apparent as the description proceeds.

Referring to the drawing illustrating my invention, the scope whereof is defined by the appended claims.

Figure 1 is a front elevation of a journal box lid assembly embodying my invention, a portion of the hood or spring housing thereof being broken away to more clearly show the construction.

Figure 2 is a sectional view of the lid assembly and a fragmentary portion of the associated journal box on the line 2—2 of Figure 1, looking in the direction of the arrows. 5

Figure 3 is a fragmentary sectional view on the line 3—3 of Figure 1, looking in the direction of 10 the arrows.

Figure 4 is a fragmentary elevational view taken on the line 4—4 of Figure 1, looking in the direction of the arrows.

Referring to the drawing in detail, like parts 15 being designated by like reference characters, a portion of a journal box 1 is shown with an ordinary form of hinge lug 2 extending from the upper wall or roof thereof to which the journal box lid assembly 3 is pivotally connected as by 20 means of a hinge pin or pintle 4. In the present embodiment, the complete journal box lid 3, comprises a closure member, plate, or lid proper 5 and hood, carrier, or spring housing member 6, said parts being movably or pin connected 25 adjacent the horizontal center line of the lid as by means of a connecting pin, pintle, or equalizer 7. The pin 7 in the present embodiment extends through outstanding brackets, loops or ears 8 on, or secured to, the lid proper or 30 plate 5 and through corresponding apertures 9 in the housing or hood portion 6, into which hood portion the brackets preferably extend, sufficient clearance being provided to permit the desired self-adjusting movement of the lid. If 35 the closure member or lid proper 5 is formed of pressed metal, the loops 8 may desirably be formed separately with the inner ends 10 passed through corresponding apertures in the lid and welded thereto as indicated at 11. 40

The lid assembly 3 is pivoted to the box by the pivot pin 4 extending through perforated ears or hinge portions 12 on the hood 6 rather than through corresponding portions on the lid proper. The hinge pin 4 may be headed and 45 locked in position in any desired manner as by having the end split or bifurcated and expanded in place in a well known manner. The corresponding lug or bearing portion 12 receiving the expanded end may have the aperture elongated 50 for properly receiving the separated prongs on the pin, whereby when locked in place, turning of said pin with respect to the housing is prevented.

In order to provide for resiliently holding the 55

lid in open or closed position, a torsion spring 13 is normally positioned between the hood or housing 6 and lid proper 5. The spring 13 preferably has a pair of coils or helical portions 14 normally resting on curved seat portions 15 on the housing or hood 6, and an intermediate loop or upwardly extending portion 16 desirably formed with a wear plate 17 or anti-friction roller (not shown) for engagement with the hinge lug 2 in the normal manner. The free ends or depending tails 18 engage in corresponding apertures 19 in the connecting pin 7, said apertures being preferably adjacent the side walls of the housing 6, so that when assembled, the pin is held in position by the ends of the spring engaging it adjacent its ends where they are received in the apertures 9 in the housing 6. In order to limit relative movement between the lid 5 and the housing 6, when the lid is open, the loops 8 are preferably formed with lateral extensions 20 overlying the ends 18 of the spring 13 and adapted to engage said spring when a slight relative movement has been effected between the lid proper 5 and the housing 6. To avoid positioning the hood 6 at too great a distance from the lid 5, that portion of the lid adjacent the coils 14 is preferably inwardly depressed or pocketed as indicated at 21 to receive the adjacent portions of said coils. In order to equalize the pressure on the lid, so that it will engage the edge of the box opening around the full periphery thereof, the lid proper 5 is preferably formed with an outstanding lug or embossment 22 normally engaged by the connecting pin 7, which construction also results in a transmission of spring pressure between the housing and lid proper, thereby preventing rattling even when the lid is open. For rigidifying the construction, the lid may be corrugated as indicated at 23 and formed as usual with a peripheral flange or lip 24.

From the foregoing disclosure, it will be seen that I have provided the two piece resiliently pressed self-adjusting lid for a journal box, which lid involves a closure portion and a hood or spring housing portion between which a torsion spring is normally disposed. On account of having the tails of the spring received in the connecting pin, said pin is locked in place without auxiliary means, and rattling is prevented by engagement of the pin with the central boss on the lid, which in turn causes a uniform application of pressure to the lid, while permitting a sufficient universal self-adjusting movement thereof relative to the carrier member or housing. Relative movement between the lid and housing, when the lid is open, is limited by the special construction of the hinging loops on the lid proper.

Although I have described a preferred embodiment of my invention, it will be understood that modifications may be made within the spirit and scope of the appended claims.

Having now described my invention, I claim:

1. In combination, a journal box having a hinge lug, a lid assembly pivotally carried thereby and comprising a hood and a lid proper movably connected adjacent the center of the latter, and a torsion spring with intermediate coiled portions engaging the hood and end portions respectively engaging the connecting means and hinge lug.

2. In combination, a journal box having a hinge lug, an articulated lid pivotally carried thereby and comprising a hood and a lid, means movably connecting said hood and lid adjacent the center of the latter, and a torsion spring disposed

between said hood and lid, engaging the lug and connecting means, respectively, at its upper and lower ends and formed with coils engaging the hood intermediate said ends.

3. In combination, a journal box having a hinge lug, a two piece lid pivotally carried thereby and comprising a hood pivoted to the lug adjacent its upper edge and to the lid proper adjacent its lower end, resilient means disposed between said hood and lid proper and engaging said lug for holding the lid in open or closed position, and means on the lid proper normally overlying the adjacent portions of the resilient means for limiting relative movement between said hood and lid.

4. In combination, a journal box having a hinge lug, a lid assembly pivotally carried thereby, and comprising a hood and a lid proper movably connected adjacent the center of the latter, and a torsion spring disposed between said hood and lid proper and comprising a spring wire formed into a pair of coils seated on the hood, a loop portion extending upwardly therebetween and normally engaging the hinge lug, the ends of said wire extending downwardly from the coils and engaging the means connecting the hood and lid proper, whereby the pressure of the spring does not cause relative rotation between the lid and hood.

5. In combination, a journal box having a hinge lug, a lid assembly pivotally carried thereby and comprising a hood and a lid proper, means movably connecting said hood and lid proper adjacent the center of the latter, and a torsion spring disposed between said hood and lid and provided with coil portions seated on the hood, an intermediate loop portion engaging the lug and the free ends or tails of the spring engaging the means connecting the hood and lid proper.

6. In combination, a journal box having a hinge lug, a lid assembly pivotally carried thereby and comprising a lid proper, a spring housing, a pin extending through the lower portion of said housing and clips embracing said pin and connected to said lid proper to hold said pin in proper position, a torsion spring with a plurality of coils seated on the housing and received in a depression on the lid proper, a loop portion of the spring between the coils normally engaging the lug, and the lower ends of said spring received in apertures in the pin connecting said lid and housing.

7. A journal box lid assembly comprising a hood and a lid proper, loops extending outwardly from the front face of the lid proper and a pin extending through said loops and registering apertures in the hood for connecting the parts, resilient means held between said hood and lid formed with an upward extension adapted to engage an associated hinge lug and lower extensions engaging the pin connecting said hood and lid proper.

8. A journal box lid assembly comprising a lid proper and a spring housing, a plurality of loops extending outwardly from the face of the lid proper, a pin extending through said loops and corresponding apertures in said housing for pivotally connecting the parts, and a torsion spring disposed between said hood and lid proper and comprising a pair of coils seated on the hood, a loop portion extending upwardly therebetween and adapted to engage an associated hinge lug, the lower ends of said spring extending downwardly from the coils and engaging the pin, the loops extending from said lid proper being formed

with lateral extensions adapted to engage the ends of said spring and limit relative movement between said lid proper and housing.

9. In a lid structure for the opening of a journal-box, the combination of a carrier member which is pivotally connected to said journal-box, a plate member for closing said opening, means for connecting said plate member to said carrier member, which means comprise a bracket 10 which is secured to said plate member and extends into said carrier member wherein a pin projects through said bracket for pivotally securing the plate member to the carrier member, whereby a sufficient universal, self-adjusting 15 movement of the plate member relatively to said carrier member is afforded, together with means for limiting such movement.

10. A journal box lid assembly comprising a hood and a lid proper, a member movably mounted 20 on the front face of said lid proper, the lower end of said hood being formed with receptacles receiving the ends of said member, and resilient means engaging the hood intermediate the ends and the member at the lower end thereof.

11. A journal box lid assembly comprising a lid proper and a spring housing, a connecting member pivotally mounted on the front face of said lid, the lower end of said spring housing being formed with receptacles receiving the ends of said 25 member, and a torsion spring disposed between said hood and lid proper and comprising a pair of coils seated on the hood, a loop portion extending upwardly therebetween and adapted to engage an associated hinge lug, the lower ends of 30 said spring extending downwardly from the coils and received in receptacles in said connecting member.

12. In combination, a journal box having a hinge lug, an articulated lid pivotally carried 40 thereby and comprising a hood and a lid, an equalizer and a lid, an equalizer movable with respect to said hood, providing for free universal angling between said hood and lid, pivotally mounted on the face of said lid and having its 45 ends interlocked with the lower end of said hood to hold the parts in assembled relation, and resilient means disposed between said hood and lid, engaging the lug and equalizer respectively at its upper and lower ends, and the hood intermediate said ends.

13. In combination, a journal box having a hinge lug, a lid assembly mounted thereon and comprising a lid proper, a spring housing and an equalizer, and means pivotally mounting said 55 equalizer on the front face of said lid proper, the lower end of said housing and equalizer being interlocked, and a torsion spring with a plurality of coils seated in the housing, a loop portion of the spring between the coils normally engaging 60 the lug and the lower ends of said spring received in apertures in said equalizer.

14. A two-piece journal box lid comprising a hood adapted to be connected to an associated journal box, a closure member and an equalizing member connecting said closure member, and hood, means pivotally mounting said equalizing member on the front face of said closure member, and resilient means disposed between said closure member and hood, engaging said hood 70 with its lower ends received in receptacles in said equalizing member and adapted to engage portions of an associated box for holding the lid in open or closed position.

15. In combination, a journal box having a hinge lug, an articulated lid pivotally carried 75

thereby and comprising a hood and a lid proper, and connecting and resilient means disposed between said hood and lid proper for uniting the same adjacent the center of the lid proper and holding the lid open or closed, said means comprising a torsion spring comprising laterally spaced elements extending from the lug at its upper end to join with the connecting means on opposite sides of the lid center, and formed with coils 10 engaging the hood intermediate its ends.

16. In combination, a journal box having a hinge lug, a lid assembly pivotally carried thereby and comprising a hood and a lid proper, and connecting and resilient means comprising means connecting the hood and lid proper, and a torsion spring consisting of a wire bent to form a pair of coils seated on the hood and disposed between it and said lid proper, and a loop portion extending upwardly therebetween and normally acting on the hinge lug, the ends of said wire extending downwardly from the coils to join with the means connecting the hood and lid proper.

17. In combination, a journal box having a hinge lug, a lid assembly pivotally carried thereby and comprising a hood and a lid proper, and resilient and connecting means disposed between said members for holding the lid assembly in open or closed position and connecting the parts thereof, said means comprising a torsion spring provided with coil portions seated on the hood, an intermediate loop portion acting on the lug, and free end portions meeting the means connecting the hood and lid proper.

18. In combination, a journal box having a hinge lug, a lid comprising a spring housing pivotally carried by said lug and a lid proper, said lid proper being formed with outstanding loops, normally covered by said housing, and a hinge pin extending through said loops and registering apertures in the spring housing for pivotally connecting said lid proper and housing, and resilient means engaging said lug and pin.

19. A journal box lid assembly comprising a hood and a lid proper, a pin with its axis disposed generally parallel to the plane of said lid and connecting said hood and lid proper adjacent the center of said lid, and a spring with an intermediate portion at all times engaging the hood and with lower end portions engaging the pin on opposite sides of the connection between the pin and lid.

20. A two piece journal box lid comprising a hood adapted to be connected to an associated journal box, a closure member, a pin connecting said closure member and hood and lying therebetween, and resilient means disposed between said closure member and hood, with an intermediate portion at all times engaging said hood and an end portion engaging said pin, so that the pressure of said means on said pin does not tend to cause rotation between the hood and closure member, and adapted to engage angularly disposed portions on an associated box for holding said lid in open or closed position.

21. In combination, a journal box having a hinge lug, a lid assembly carried thereby and comprising a hood and a lid proper, a pivot member connecting said hood and lid proper, and an actuating spring housed between said hood and lid proper and exerting pressure on said pivot member, said lid proper being connected to said pivot member by outstanding lid loops, through which said member loosely passes, for angling about the axis of said pivot member and about an axis disposed at an angle to said member.

22. In combination, a journal box having a hinge lug and a lid assembly pivotally carried thereby and comprising a retainer and a lid proper connected adjacent the center of the latter for free universal movement by means including a pivot member extending substantially parallel to said lid proper, and resilient means com-

HOWARD T. CASEY.
